GAUGING MEANS FOR LAWN MOWERS

Frank D. Wulff, Chicago, Ill.

Application November 23, 1944, Serial No. 564,836

3 Claims. (Cl. 33—181)

1

The present invention relates to devices for setting or gauging the relation of cutting blades of lawn mowers and the like.

Among the objects of the invention is to provide a novel gauge-type setting device for evening the setting or relation of the rotary blade or blades with respect to the stationary blade or the like of a lawn mower, and comprising relatively adjustable parts of which one part may be contacted with the stationary blade and the other part contacted with the shaft of the rotary blade means whereby both ends of the blades may be adjusted to be even and in accordance with the adjusted setting of the gauge.

Another object of the invention is to provide a novel device of the character disclosed and which may have also contacting means on one of the members which may be set against the edge of the rotary blade to gauge the position of the contacting member to contact the cutting edge of the stationary blade and still have the other contacting member in contact with the shaft, the contacting surfaces of the two first-mentioned contacting elements being in a common plane.

Other objects, advantages, capabilities, features and the like are comprehended by the invention as will later appear and as are inherently possessed by the invention.

Referring briefly to the drawing:

Fig. 1 is a side view in elevation of the device constructed in accordance with the invention;

Fig. 2 is a front view thereof;

Fig. 3 is a rear view thereof;

Fig. 4 is a part sectional view, on an enlarged scale, taken in a plane represented by line 4—4 in Fig. 3 of the drawing;

Fig. 5 is a transverse sectional view taken in a plane represented by line 5—5 in Fig. 3 of the drawing;

Fig. 6 is a perspective view of a part of the device; and

Fig. 7 is a perspective view of another part of the device.

Referring more in detail to the drawing, the device is shown as comprising a pair of relatively slidable elongated members 1 and 2 of which the member 1 has at its lower end a heel part 3, adapted to contact the edge of the stationary blade when in use as later explained, and a laterally extending toe part 4 adapted to contact the upper face of the cutting edge of the stationary blade adjacent its cutting edge, and at its upper end with a laterally extending finger or flange part 5 to serve as a finger piece when adjusting the device as later explained. At an

intermediate part of the member 1 is provided an elongated slot 6.

The member 2 has at its lower end laterally extending and reversely curved guide flanges 7 and 8 adapted to encompass the edge portions of the member 1 and to slide along the same. Near or at the lower end of the member 2 is provided a laterally or rearwardly extending toe part or projection 9 which may have a flange or leg 10 suitably secured to the member 2. At the upper end of the member 2 is provided a laterally extending finger or flange part 11 which serves as a finger coordinately with the flange 5. By pressing the finger pieces 5 and 11, between the thumb and finger of the user, the members are caused to relatively slide.

At an intermediate part the member 2 has a threaded element 12, which may be in the form of a nut, suitably secured to the member 2 as by way of solder 13 or the like. This element 12 is located to have its threaded part opposite the slot 6 and a suitable hole 14 provided in the member 2. In threaded engagement with this element 12 is the threaded stem 15 of a finger clamp having a finger piece 16 and a thrust collar or head 17 adapted to clamp on the member 1, the stem 15 passing through the slot 6 and the opening 14, as shown, to hold the members 1 and 2 in adjusted relation.

30 The device is particularly adapted to be used with the cutter means of a lawn mower or the like, and, as shown in Fig. 1, such means comprises a relatively stationary blade 18 carried by or fixed to a blade holder 19 supported on a shaft 20 carried by the frame 21 of the mower. The frame 21 also carries a bar 22 which may be fixed to the frame and in this bar are adjusting screws 23 the ends of which are adapted to engage saddles or shoulders 24 provided on the holder 19, as shown in Fig. 1. By adjusting the screws 23, the angular relation of the holder 19 and the blade 18 relative to the axis of the shaft 20 may be had as desired so that the blade 18 will be in proper shearing position for the cutting blades. 40 On the frame 21 is also mounted a shaft 25 for rotatably carrying a rotary blade holder 26 to which is secured one or more blades 27, the cutting edge 28 of which travels in a circular path represented by the arrows 29 to have shearing function with the cutting edge 30 of the stationary blade 18, as shown in Fig. 1.

The device of the present invention is used to gauge the relation of the cutting edge 30 in proper shearing relation with the cutting edge 28. This is effected by first adjusting the position

of an end of the blade 18, by way of adjusting the screws 23 at each end of the blade 18, so that the corresponding end of the blade 27 will have the desired position or shearing relation of the cutting edges 28 and 30. Then the device of this invention is applied in place by resting the toe 4 on the cutting edge 30 and then by moving the member 2 with the guide 7-8 upward along the member 1, to bring the toe 9 into contact with the shaft 25, and then the screw 15-16 is tightened to hold the members 1 and 2 clamped together. This device is then moved to the other end of the blade 18 to place the toe 4 on the edge 30 at such end of the blade and then toe 9 is swung to position under the shaft 25. If the toe 9 contacts the underside of the shaft 25, the cutting edge 30 is in correct position. If the toe 9 is spaced below the shaft 25 the screws 23 are adjusted to raise the blade 18 until the toe 9 contacts the underside of the shaft 25; and if the toe 9 is too high to come under the shaft 25 the screws 23 are so adjusted as to lower the blade 18 until the toe can come just under the shaft 25.

The device also may have fixed to the lower end portion or heel 3 another toe 31 having its upper surface 32 in the same plane as the lower surface of the toe 4, and this toe 31 may have a flange 33 suitably secured to the lower end part of the heel 3. This toe 31 is used by bringing the upper face 32 thereof against the cutting edge 28 of the rotary blade 27 and then adjusting the toe 9 to contact with the underside of the shaft 25, whence the lower face of the toe 4, being in the same plane as the face 32, will be at the correct position to coincide with or contact the edge 30 of the blade 18. If the edge 30 does not so contact, then the screws 23 will be so adjusted as to effect such contact. Therefore, adjustment may be effected in this manner at both ends of the blade 28 and the blade 27.

While I have herein described and upon the drawing shown an illustrative embodiment of the invention it is to be understood that the invention may comprehend other constructions, details, arrangements of parts, features and the like without departing from the spirit of the invention.

Having thus disclosed the invention, I claim:

1. A gauging means for a lawn mower which has a frame carrying a relatively adjustable stationary blade and a rotary blade rotatable on a shaft carried by said frame; said gauging means comprising two relatively flat and elongated members assembled in face-to-face rela-

tion for longitudinal sliding movement with respect to each other, one of said members having a laterally-extending toe adjacent the lower end thereof with a flat lower surface adapted to be placed on the upper surface of the stationary blade of the mower and having a laterally-extending finger piece at the upper end thereof; the other of said members being of lesser length than said first mentioned member and having a laterally extending toe adjacent the lower end thereof disposed at that side of the assembled members opposite that from which the toe on the first-mentioned member extends, said toe of the second-mentioned member having a flat upper surface adapted to be placed beneath the shaft of the rotary blade of the mower, and said second-mentioned member having a laterally-extending finger piece at the upper end thereof and disposed at the same side of said member as the laterally extending toe thereof; one of said members having relatively short laterally-extending, reversely curved guide flanges along the side edges thereof engaging the side edges of the other member to maintain the members in assembled relation and to permit longitudinal sliding movement of said members with respect to each other; and clamping means connected to said members for holding them in adjusted relation, said clamping means comprising a threaded part fixed to one of said members, a clamping element threaded into said part and extending through an elongated slot provided in the other of said members and also having a clamping head for clamping engagement with said last-mentioned member.

2. A gauging device as defined in claim 1 wherein the finger piece at the upper end of the first mentioned member is disposed at the same side of the assembled members as the finger piece at the upper end of the second-mentioned member, whereby said finger pieces may be readily engaged by the thumb and finger of an operator to effect relative sliding movement of the members when the clamping means is released.

3. A gauging device as defined in claim 1 wherein the first-mentioned member has a second laterally-extending toe adjacent its lower end and disposed on that side of said member opposite to the other toe thereon, the upper surface of said second toe being flat and in the same plane as the lower flat surface of said other toe.

FRANK D. WULET.
